CARL J. PRINZLER, OF INDIANAPOLIS, INDIANA, ASSIGNOR TO VON DUPRIN FIRE EXIT LATCH COMPANY, A COPARTNERSHIP COMPOSED OF VONNEGUT HARDWARE CO., A CORPORATION OF INDIANA, AND CARL J. PRINZLER AND HENRY H. DUPONT, BOTH OF INDIANAPOLIS, INDIANA.

LOCK

1,158,845.

Specification of Letters Patent.

Patented Nov. 2, 1915.

Application filed August 14, 1914. Serial No. 856,753.

To all whom it may concern:

Be it known that I, CARL J. PRINZLER, a citizen of the United States, residing at Indianapolis, in the county of Marion and State 5 of Indiana, have invented a new and useful Lock, of which the following is a specification.

The object of my invention is to produce a lock especially designed for use in connection with a so-called "panic bar" which normally lies across the inner face of the door in such manner that persons crowding against the same will automatically cause the release of the door, the construction of 10 my present lock being such that the single locking member, which is in the form of a latch bolt, may be locked against retraction from the exterior of the door without interfering with the retraction of the latch bolt 15 by means of the panic bar; which will also permit the retraction and holding of the latch bolt in retracted position by manipulation of a key; and which will also automatically withdraw the dogging mechanism 20 from the latch bolt when the door is open.

The accompanying drawings illustrate my invention.

Figure 1 is an elevation of the lock, with the face plate removed, and with the parts 30 in the positions occupied when the door is closed and locked against external manipulation; Fig. 2 a similar view when the latch bolt has been retracted by manipulation of the panic bar; Fig. 3 a similar view with 35 the parts in the positions occupied when the latch bolt has been released for manipulation by the external thumb piece; Fig. 4 a similar view with the parts in the positions occupied when the latch bolt has been re- 40 tracted and locked in retracted position; Fig. 5 a section on line 5—5 of Fig. 3; Fig. 6 a section on line 6—6 of Fig. 3; and Figs. 7 and 8 perspectives of the bolt which is used for dogging the thumb piece block.

The lock has been illustrated in the form 45 of a mortise lock with a cylinder key lock of common type for controlling its manipulation and in the drawings 10 indicates the main casing comprising the face plate 11 having an opening 12 through it for the latch bolt 13 and an opening 14 for the dog 50 controlling plunger 15. The latch bolt 13 is pivoted at 17 in the face plate 11 and piv-

totally connected to said bolt at 18 is the latch bolt stem 19 provided near its outer 55 end with an inwardly presented dogging shoulder 21 and at its inner end with a laterally extending plate 22 by means of which the stem may be manipulated. Surrounding stem 19 is a spring 23 which acts against the 60 stump 24 to normally project the latch bolt from the casing.

Near the lower inner corner of the casing 10 are mounted two sliding thumb piece heads 25 and 26, the head 25 overlying the 65 head 26 so that two of the edges of these heads lie substantially in the same plane, sliding against the stumps 27, 27 and provided with notches 25' and 26', respectively. These two heads 25 and 26 are individually 70 accessible from the exterior of the casing and are independently movable. Slidably mounted between the stumps 27 is a dogging bar 28 provided upon one face with a stump 29 adapted to be received in either one of a 75 pair of notches 30, 30 formed in the upper and lower edges of a dog 31 provided at one corner with a tail 32 which is formed for projection into one or the other of the notches 25' and 26', depending upon the pos- 80 itioning of the dog 31 relative to the dogging bar 28. Pivoted on the stump 33 is a lever 34 having a broad end 35 positioned to be engaged by either one of the heads 25 and 26. The lever 34 also normally engages one 85 arm of a lever 36 which is pivoted on the stump 37. The end of lever 36 opposite from that which is engaged by the lever 34 is arranged to be engaged by a lever 38 which is pivoted upon a stump 39 and near 90 this end of lever 36 is a cam lug 40.

Pivoted upon stump 37 and overlying lever 36 and extending in a general direction parallel with stem 19 is a lever 41 having an upwardly extended cam tip 42. Lever 41 is 95 perforated at 43 for the reception of a pin 44 carried by lever 36, the pin 44 being somewhat smaller than the perforation 43. Pivoted upon the stump 45 and lying between levers 36 and 41 is a latch dogging 100 lever 46, the free end of which is adapted under proper conditions to be projected behind the dogging shoulder 21. Lever 46 at its inner end is provided with a cam tail 48 and at an intermediate point with a cam 105 finger 49 arranged for coaction with the lug

40. Lever 41 is engaged by a spring 51 which normally urges the same upwardly.

Slidably mounted in the casing 10 substantially parallel with stem 19 is a key bar 52 formed at 53 for the reception of a key or key-controlled finger 54. The bar 52 carries a stump 55 upon which is pivoted a tumbler 56, said tumbler having one end 57 associated with the portion 53 of the key bar so as to be controlled by the key or lever 54 and this tumbler is provided with a finger 58 which coöperates with a stump 59 in casing 10 to control the manipulation of the bar 52 and prevent its accidental displacement from either extreme position. Tumbler 56 is also provided on its upper edge with a cam finger 61 and a dogging cam finger 62. The tumbler 56 is normally urged to the position shown in full lines in Figs. 1, 2 and 4 and in dotted lines in Fig. 3 by a spring 63 which is carried by the bar 52.

Pivoted on stump 39 is a lever 64 having a block 65 formed for engagement by the fingers 61 and 62 of tumbler 56 and also having a tip 66 adapted to be engaged, in one position by the arm 54. Lever 64 upon the face opposite to that shown in the drawings, is provided with a lug 67 (dotted lines Figs. 1 and 2) which overlies the upper edge of lever 38.

The sliding bar 52 is provided with a depending finger 68 having a notch 69 in which is laid the stem 15' of the plunger 15, a spring 71 surrounding said stem and acting upon the plunger and finger 68 to normally project the plunger from the face plate of the casing. At its inner end the plunger 15 is provided with a cross piece 72 which serves to limit the movement of the plunger relative to the bar 52 and also acts upon the cam finger 42 of the lever 41. Bar 52 carries a depending finger 73 which lies between fingers 48 and 49 of lever 46 and coacts with the finger 48 to swing said lever 46.

Plunger 15 is provided at its outer end with a head 15' which is oppositely beveled from its middle by two diverging vertical planes so that lateral movement of the entire lock relative to an adjacent strike will cause an inward projection of the plunger if it is in outwardly projected position.

Pivoted on stump 81 is a lever 82 which engages the dogging bar 28 and the sliding bar 52.

The above described lock is primarily designed for use with a door equipped upon its outer face with an ordinary thumb piece and upon its inner face with a "panic bar" which extends across the face of the door and is capable of movement laterally of the plane of the door and the operation is as follows: The parts will normally lie in the positions shown in full lines in Fig. 3 except that the key controlled arm 54 will lie

in the position shown in Figs. 1 and 2. In these positions of the parts, the plunger 15 is held retracted by the sliding bar 52 and cam finger 73 of said bar 52 has acted upon the cam finger 48 of lever 46 to withdraw said lever from behind the dogging shoulder 21 of stem 19; lever 82 has acted upon the dogging bar 28 to retract dog 32 from head 25 and cam finger 61 has acted upon block 65 to throw the end 66 of lever 64 down into the path of movement of the arm 54. In these positions of the parts, the latch 13 is free for manipulation either by a force applied directly to the latch or by forces applied to the cross head 22 through lever 36 so that an upwardly directed force acting upon either of the heads 25 and 26 will swing lever 34 against lever 36 and drive said lever against cross head 22 to move stem 19 and retract the latch bolt.

Fig. 3 shows the condition of the parts just as the bar 52 has been driven by arm 54 to the externally unlocked position and before the tumbler 56 has resumed its normal position, and if the key be turned in the direction indicated by the arrow in Fig. 3, past the normal withdrawing position of the key, the arm 54 will come into engagement with the tip 66 of lever 64 and throw said lever downwardly to the position shown in Fig. 4. This movement of lever 64 brings lug 67 into engagement with lever 38 and causes said lever to swing downwardly, its end coming into engagement with the adjacent end of lever 36 and swinging said lever to retract the latch bolt. As lever 64 moves downwardly, one end of its block 65 engages the dogging finger 62 of the tumbler 56, swinging said tumbler downwardly so that, when the lever 64 has been carried to its lowest position, the tumbler 56 may spring backwardly to the position shown in full lines in Fig. 4 in which position the dogging finger 64 overlies the block 65 and holds lever 64 in its depressed position, thus locking the latch bolt in retracted position so that the door will be free for movement without necessity of manipulating any of the operating members normally provided for that purpose.

When the lever 64 has thus been depressed and locked in its depressed position, the key may be turned backwardly about half a turn so as to bring the arm 54 to the position shown in Figs. 1 and 2 and the key withdrawn. By turning the key in the direction opposite to that indicated by the arrow in Fig. 3, arm 54 will be first brought into contact with the tumbler 56 so as to depress said tumbler, whereupon lever 64 is immediately released and, because of the action of spring 23 through levers 36 and 38, lever 64 will be automatically thrown up to the position shown in Fig. 3 and, if desired, the arm 54 may be immediately returned to its normal

position and the key withdrawn without any movement of the bar 52 and thus without any dogging action upon head 25 and consequent locking of the door from exterior manipulation. If desired, however, the key may be continued in its movement (opposite that indicated by the arrow in Fig. 3) and the bar 52 shifted to the position shown in Figs. 1 and 2. This shifting of the bar 52 will, if the door be open and the face plate 11 be thus away from the coöperating strike, permit the projection of the plunger head 15' to the position indicated by dotted lines in Fig. 1 so that the cross head 72 of the plunger 15 will engage the cam finger 42 of lever 41 to move it downwardly to the position indicated by dotted lines in Fig. 1 and thereby, through perforation 43 and pin 44, swing the dogging lever 46 upwardly from behind shoulder 21, the said dogging lever 46 having been just previously projected to the position shown in full lines in Fig. 1 by the withdrawal of the cam finger 73 from engagement with the cam finger 48. This automatic action of the plunger 15 upon the lever 41 is important because it immediately frees the latch bolt for manipulation either by the thumb piece, the panic bar, or by mere engagement of the latch bolt with the strike of an adjacent door or post as the door is swung to closed position.

Whenever the door is swung to its closed position with the parts as above described, the latch bolt will be first moved inwardly by coöperation with the strike plate and at the same time the head 15' of the plunger 15 coöperating with an imperforate portion of the strike plate, will be moved inwardly so as to free levers 41 and 46 but this action on the plunger 15 takes place after shoulder 21 has passed beneath the free end of lever 46 so that the inward movement of the latch bolt is not interfered with but, as soon as the door has reached its final or closed position and the latch bolt snaps into the strike plate, the dogging lever 46 drops behind shoulder 24 and thus automatically locks the latch bolt against any retraction by shaking the door or by means of the insertion of any instrument between the face plate 11 and the strike plate. The parts will thus be in the positions indicated in Fig. 1, the shifting of the bar 52 having operated upon lever 82 to throw the dog 32 into notch 25' and thus lock the mechanism against manipulation by means of the external thumb piece which engages the head 25. The head 26 is free for manipulation by movement of the panic bar (not shown) so that when said head 26 is thrown up to the position shown in Fig. 2, it acts on lever 34 which in turn acts upon lever 36. There is a slight lost motion between the projected position of shoulder 21 and the dogging lever 46 and lug 40 is in engagement with finger 49 so that the

initial movement of lever 36, while producing a very small movement of the latch bolt stem 19 produces, through the cams 40 and 49, a rapid movement of the dogging lever 46 so as to retract it fully from behind shoulder 21 before there is any material movement of stem 19 whereupon the further upward movement of head 26 serves to fully retract the latch bolt. 70

When the parts are in the positions shown in Fig. 1, lever 64 has been moved, by the action of cam finger 62 against block 65, to a position where the tip 66 is entirely beyond the path of movement of the arm 54 so that, when an unlocking of the external manipulator or thumb piece is desired, the arm 54 may be swung down in the direction indicated by the arrow in Fig. 3 to first engage the tumbler 56 so as to withdraw its lug 58 from behind stump 59 and then shift the bar 52 to the right into the position shown in Fig. 3, this operation, by reason of the co-action between finger 61 and block 65 bringing the tip 66 of lever 64 down to the position shown in Fig. 3 where it is in the path 80 of movement of arm 54 if said arm is carried far enough. 85

I claim as my invention:

1. In a lock, the combination with the casing, of a latch bolt yieldingly projected from the casing and provided with an inwardly presented shoulder, a dogging lever arranged to lie behind said shoulder, a key-controlled slide, a plunger carried by said slide and yieldingly movable relative thereto to be yieldingly projectable from the casing, and means operated on by said plunger for retracting the dogging lever from behind the latch bolt when the plunger is projected into the casing. 95

2. In a lock, the combination with the casing, of a latch bolt yieldingly projected from the casing and provided with an inwardly presented shoulder, a dogging lever arranged to lie behind said shoulder, a key-controlled slide, a plunger carried by said slide and yieldingly movable relative thereto to be yieldingly projectable from the casing, means operated on by said plunger for retracting the dogging lever from behind the latch bolt 100 when the plunger is projected into the casing, and cam members carried by the slide and dogging lever whereby the dogging lever is moved into and out of dogging position by reciprocation of the slide. 105

3. In a lock, the combination with a casing, of a latch bolt yieldingly projectable from the casing and provided with an inwardly presented shoulder, a dogging lever arranged to lie behind said shoulder and provided with a cam, a cam lever connected with said dogging lever and normally urged in one direction to move the dogging lever to dogging position, a plunger yieldingly projectable from the casing and provided with a 115 120 125 130

cam end for coöperation with a strike, said plunger having a portion engaging said cam lever to retract the dogging lever from dogging position when the plunger is projected from the casing.

4. In a lock, the combination with a casing, of a latch bolt yieldingly projectable from the casing and provided with an inwardly presented shoulder, a dogging lever 10 arranged to lie behind said shoulder, a cam lever connected with said dogging lever and normally urged in one direction to move the dogging lever to dogging position, a plunger yieldingly projectable from the casing 15 and provided with a cam end for coöperation with a strike, said plunger having a portion engaging said cam lever to retract the dogging lever from dogging position when the plunger is projected from the casing.

5. In a lock, the combination with a casing, a yieldingly projectable latch bolt having an inwardly presented shoulder, a lever engaging said latch bolt for retracting the same, a dogging lever arranged to lie behind said 25 inwardly presented shoulder, a pair of co-operating cam pieces carried by said two levers whereby movement of the first-mentioned lever to latch-retracting position will inwardly withdraw the dogging lever from 30 dogging position, a key-controlled lever, means for shifting said lever into and out of key-actuatable position, and means controlled by said last-mentioned lever for driving the first-mentioned lever to latch-retracting 35 position.

6. In a lock, the combination with a casing, a yieldingly projectable latch bolt having an inwardly presented shoulder, a lever engaging said latch bolt for retracting the 40 same, a dogging lever arranged to lie behind said inwardly presented shoulder, a pair of co-operating cam pieces carried by said two levers whereby movement of the first-mentioned lever to latch-retracting position will 45 inwardly withdraw the dogging lever from dogging position, a key-controlled lever, means for shifting said lever into and out of key-actuatable position, means controlled by said last-mentioned lever for driving the 50 first-mentioned lever to latch-retracting position, and key-controlled means for dogging said key-controlled lever in latch retracting position.

7. In a lock, the combination with the casing, of a yieldingly projectable latch bolt, a lever operating upon the same to retract it, a second lever operating upon the first lever to drive it in latch-retracting direction, a key-controlled lever arranged to act upon 55 said second lever in latch retracting direction, a key controlled slide, a tumbler mounted on said slide, a stump coöoperating with said tumbler, cam and catch portions carried by said tumbler and coöperating with the 60 key-controlled lever to shift the same into 65 key-controlled lever to shift the same into

and out of key-actuatable position and to hold the same in latch-retracting position, a cam lever connected with the dogging lever, and a plunger carried by the key bar and yieldingly movable relative thereto and yieldingly projectable from the casing, said plunger having a portion engaging said cam lever to retract the dogging lever from dogging position when the plunger is projected from the casing.

8. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch-retracting direction, a key-controlled slide, a tumbler mounted on said slide, a stump coöperating with said tumbler, and cam and catch portions carried by said tumbler and coöperating with the key-controlled lever to shift the same into and out of key-actuatable position and to hold the same in latch retracting position.

9. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch retracting direction, a key controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, a cam lever connected with the dogging lever, a plunger carried by the key bar and yieldingly movable relative thereto and yieldingly projectable from the casing, said plunger having a portion engaging said cam lever to retract the dogging lever from dogging position when the plunger is projected from the casing, and coöperating cam portions carried by said key bar and dogging lever.

10. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch-retracting direction, a key-controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, and coöperating cam portions carried by said key bar and dogging lever.

11. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch retracting direction, a key controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, a cam lever connected with the dogging lever, a plunger carried by the key bar and yieldingly movable relative thereto and yieldingly projectable from the casing, said plunger having a portion engaging said cam lever to retract the dogging lever from dogging position when the plunger is projected from the casing, and coöperating cam portions carried by the key bar and the dogging lever and coöperating cam portions carried by the dogging lever and the latch-actuating lever.
12. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch-retracting direction, a key-controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, and coöperating cam portions carried by the dogging lever and latch-actuating lever.
13. In a lock, the combination with the casing, of a yieldingly projectable latch bolt, a lever operating upon the same to retract it, a second lever operating upon the first lever to drive it in latch-retracting direction, a key-controlled lever arranged to act upon
14. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch-retracting direction, a key-controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, a cam lever connected with the dogging lever, a plunger carried by the key bar and yieldingly movable relative thereto and yieldingly projectable from the casing, said plunger having a portion engaging said cam lever to retract the dogging lever from dogging position when the plunger is projected from the casing, and coöperating cam portions carried by the key bar and the dogging lever and coöperating cam portions carried by the dogging lever and the latch-actuating lever.
15. In a lock, the combination with the casing, of a yieldingly projectable latch bolt, a lever operating upon the same to retract it, a second lever operating upon the first lever to drive it in latch-retracting direction, a key-controlled lever arranged to act upon said second lever in latch-retracting direction, a key-controlled slide, a tumbler mounted on said slide, a stump coöperating with said tumbler, cam and catch portions carried by said tumbler and coöperating with the key-controlled lever to shift the same into and out of key-actuatable position and to hold the same in latch-retracting position, and coöperating cam portions carried by the key bar and the dogging lever and coöperating cam portions carried by the dogging lever and the latch-actuating lever.
16. In a lock, the combination with the casing, of a yieldingly projectable latch bolt, a lever operating upon the same to retract it, a second lever operating upon the first lever to drive it in latch-retracting direction, a key-controlled lever arranged to act upon

Witnesses:
